US0D1049060S

(12) **United States Design Patent** (10) **Patent No.:** **US D1,049,060 S**
(45) **Date of Patent:** **** Oct. 29, 2024**

(54) **MULTI REMOTE CONTROLLER**

(71) Applicant: **MITSUBISHI ELECTRIC CORPORATION**, Tokyo (JP)

(72) Inventor: **Shinya Ishihama**, Tokyo (JP)

(73) Assignee: **MITSUBISHI ELECTRIC CORPORATION**, Tokyo (JP)

(**) Term: **15 Years**

(21) Appl. No.: **29/869,110**

(22) Filed: **Dec. 21, 2022**

(30) **Foreign Application Priority Data**

Jun. 29, 2022 (JP) ..... 2022-013873 D

(51) **LOC (14) Cl.** **14-03**

(52) **U.S. Cl.**

USPC **D13/168; D10/50**

(57) **CLAIM**

The ornamental design for a multi remote controller as shown and described.

DESCRIPTION

FIG. 1. is a front perspective view of a multi remote controller showing my new design;

FIG. 2. is a rear perspective view thereof;

FIG. 3. is a front view thereof;

FIG. 4. is a rear view thereof;

FIG. 5. is a top plan view thereof;

FIG. 6. is a bottom view thereof;

FIG. 7. is a right side view thereof; and,

FIG. 8. is a left side view thereof.

The broken lines showing of the multi remote controller is included for the purpose of illustrating portions of the multi remote controller and forms no part of the claimed design.

1 Claim, 8 Drawing Sheets
